REFERENCE TO RELATED APPLICATIONS

This application references U.S. patent application Ser. No. 18/222,272, filed Jul. 14, 2023, which claims the benefit of U.S. Provisional Application Nos. 63/441,946, filed Jan. 30, 2023, 63/447,380, filed Feb. 22, 2023, and 63/466,836, filed May 16, 2023, each of which is hereby specifically incorporated by reference herein in its entirety. This application also references U.S. patent application Ser. No. 17/834,999, filed Jun. 8, 2022, (issued as U.S. Pat. No. 11,780,666 on Oct. 10, 2023), which is a continuation application of U.S. patent application Ser. No. 17/502,599, filed Oct. 15, 2021 (issued as U.S. Pat. No. 11,634,265 on Apr. 25, 2023), which is a continuation of U.S. patent application Ser. No. 17/123,673, filed Dec. 16, 2020 (issued as U.S. Pat. No. 11,214,427 on Jan. 4, 2022), which is a continuation application of U.S. patent application Ser. No. 16/414,309, filed May 16, 2019 (issued as U.S. Pat. No. 10,882,682 on Jan. 5, 2021), which is a divisional application of U.S. patent application Ser. No. 15/677,738, filed Aug. 15, 2017 (issued as U.S. Pat. No. 10,583,977 on Mar. 10, 2020), which claims the benefit of U.S. Provisional Application Nos. 62/375,555, filed on Aug. 16, 2016, 62/419,894, filed on Nov. 9, 2016, and 62/437,365, filed on Dec. 21, 2016. This application also references U.S. patent application Ser. No. 18/393,116, filed Dec. 21, 2023. The entire disclosure of each of the above applications is incorporated herein by reference in its entirety.

TECHNICAL FIELD

This disclosure relates to packaging. More specifically, this disclosure relates to insulated packaging.

BACKGROUND

In various aspects, packaging elements can be in need of insulation. Isolating contents from the outside can be challenging. In particular, systems that can be arranged to address some insulation challenges can be difficult to produce, requiring multiple steps to assemble any packaging elements.

SUMMARY

A packaging assembly includes an outer box, the outer box including a first main panel connected to a second main panel, a third main panel connected to the second main panel, and a fourth main panel connected to the third main panel, the fourth main panel connected to the first main panel; an insert, an insert connected to at least two of the main panels of the outer box, the insert including a first main panel connected to a second main panel; a third main panel connected to the second main panel; and a fourth main panel connected to the first main panel and the third main panel, wherein at least one support formation is arranged between at two of the four main panels, wherein each support formation connects the insert to the outer box.

A method of arranging a packaging assembly in an expanded state includes obtaining a collapsed packaging assembly, the collapsed packaging assembly including a blank for forming an outer box, the blank comprising a first main panel, a second main panel connected to the first main panel, a third main panel connected to the second main panel, and a fourth main panel connected to the third main

5 panel; an insert connected to the second main panel and the third main panel of the blank, the insert including a first main panel connected to a first support formation; a second main panel connected to the first support formation; a third main panel connected to the second main panel; a second support formation connected to the third main panel; a fourth main panel connected to the support formation; and the fourth main panel connected to the first main panel; bending the first main panel of the blank with respect to the second main 10 panel of the blank; bending the second main panel of the blank with respect to the third main panel of the blank; bending the third main panel of the blank with respect to the fourth main panel of the blank; connecting the fourth main panel of the blank to the first main panel of the blank such 15 that the insert arranges within a box defined by formation of the blank.

A packaging assembly includes an outer box, the outer box including a first main panel connected to a second main 20 panel, a third main panel connected to the second main panel, and a fourth main panel connected to the third main panel, the fourth main panel connected to the first main panel; an insert arranged within the outer box and defining at least one gap between the insert and the outer box, the 25 insert including a first main panel connected to a second main panel; a third main panel connected to the second main panel; and a fourth main panel connected to the first main panel and the third main panel, wherein at least one support formation is arranged between at two of the four main 30 panels, wherein each support formation connects the insert to the outer box.

Various implementations described in the present disclosure may include additional systems, methods, features, and advantages, which may not necessarily be expressly disclosed herein but will be apparent to one of ordinary skill in the art upon examination of the following detailed description and accompanying drawings. It is intended that all such systems, methods, features, and advantages be included within the present disclosure and protected by the accompanying claims.

BRIEF DESCRIPTION OF THE DRAWINGS

The features and components of the following figures are 45 illustrated to emphasize the general principles of the present disclosure. Corresponding features and components throughout the figures may be designated by matching reference characters for the sake of consistency and clarity.

FIG. 1 is a perspective view of a packaging assembly in 50 accord with one aspect of the current disclosure.

FIG. 2 is a plan view of a blank formable into an outer box of the packaging assembly of FIG. 1.

FIG. 3 is a plan view of a blank formable into an insert of the packaging assembly of FIG. 1.

FIG. 4 is a perspective view of the insert formed from the blank of FIG. 3.

FIG. 5A is a perspective view of a packaging subassembly formable into the packing assembly of FIG. 1 in a collapsed state.

FIG. 5B is a perspective view of the packaging subassembly of FIG. 5A formed into an expanded state.

FIG. 6 is a perspective view of a bottom insulation pad for use with the packaging assembly of FIG. 1.

FIG. 7 is a perspective view of a bottom insulation cover for use with the packaging assembly of FIG. 1.

FIG. 8 is a plan view of a blank formable into a vented cover for use with the packaging assembly of FIG. 1.

FIG. 9A is a perspective view of a vented cover with the packaging assembly of FIG. 1. FIG. 9B is another perspective view of the vented cover of FIG. 9A.

FIG. 10A is side view of an insulation element of the packaging assembly of FIG. 1. FIG. 10B is a side view of the insulation element of FIG. 10A.

FIG. 11A is a perspective view of the packaging assembly of FIG. 1 including the bottom insulation pad of FIG. 6.

FIG. 11B is a perspective view of the packaging assembly of FIG. 1 including the bottom insulation cover of FIG. 7.

FIG. 11C is a perspective view of the packaging assembly of FIG. 1 including the vented cover of FIGS. 9A-9B.

DETAILED DESCRIPTION

Disclosed is a packaging assembly and associated methods, systems, devices, and various apparatus. It would be understood by one of skill in the art that the disclosed packaging assembly is described in but a few exemplary embodiments among many. No particular terminology or description should be considered limiting on the disclosure or the scope of any claims issuing therefrom.

One embodiment of a packaging assembly 1000 is disclosed and described with reference to FIG. 1. The packaging assembly 1000 can comprise an outer box 2000. The packaging assembly 1000 can comprise an insert 3000. The packaging assembly 1000 can comprise at least one insulation element 4000a, 4000b. In various aspects, features and elements can be modified as would be understood by one of ordinary skill in the art. No particular configuration, element, or aspect of the disclosed packaging assembly 1000 should be considered limiting on the scope of any claims issuing therefrom.

A blank 200 that can be formed into the outer box 2000 can be seen with reference to FIG. 2. The blank 200 can comprise a first main panel 210, a second main panel 220, a third main panel 230, and a fourth main panel 240. The first main panel 210 can be connected to the second main panel 220 by a line 212. In various aspects, the current disclosure references "lines." In various aspects, a "line" or a plurality of "lines" can refer to bends, perforations, cuts, creases, or combinations of bends, cuts, perforations, and creases. In various aspects, perforations can be $\frac{3}{8}$ inches; in various aspects, cuts can be $\frac{1}{4}$ inches; in various aspects, perforations and cuts can be of variant sizes. If not specified in the disclosure, one of skill in the art would understand that various lines described herein can be interchangeable between various aspects of the current disclosure, and one of skill in the art would not understand any particular embodiment of "line" or "lines" to be limiting on the scope of the disclosure. The second main panel 220 can be connected to the third main panel 230 by a line 222. The third main panel 230 can be connected to the fourth main panel 240 by a line 232. The fourth main panel 240 can be connected to a connection panel 250 by a line 242. The connection panel 250 can be arranged to be secured to the first main panel 210 via glue, adhesive, welding, mechanical interlocking, or various other methods of affixing elements.

A first top panel 214 can be connected to the first main panel 210 by a line 216. A second top panel 224 can be connected to the second main panel 220 by a line 226. A third top panel 234 can be connected to the third main panel 230 by a line 236. A fourth top panel 244 can be connected to the fourth main panel 240 by a line 246.

A first bottom panel 218 can be connected to the first main panel 210 by a line 219. A second bottom panel 228 can be

connected to the second main panel 220 by a line 229. A third bottom panel 238 can be connected to the third main panel 230 by a line 239. A fourth bottom panel 248 can be connected to the fourth main panel 240 by a line 249.

A glue pad 255 can be arranged on the second main panel 220 proximate the line 212. A glue pad 265 can be arranged on the third main panel 230 proximate the line 232. Each glue pad 255, 265 can be a pad of glue or other adhesive in various aspects. Each glue pad 255, 265 can be a location for affixing apparatus as discussed in depth below. In various aspects, various connection means-including those not requiring glue-can be used in various configurations. In various aspects, glue pads 255, 265 can be obviated by other methods of connection.

A blank 300 formable into the insert 3000 can be seen with reference to FIG. 3. The blank 300 can comprise a first main panel 310, a second main panel 320, a third main panel 330, and a fourth main panel 340. A connection panel 350 can be connected to the fourth main panel 340 by a line 345. The second main panel 320 can be connected to the third main panel 330 by a line 325. A support formation 360 can be arranged between and connected to the first main panel 310 and the second main panel 320. Similarly, a support formation 380 can be arranged between and connected to the third main panel 330 and the fourth main panel 340. Each support formation can comprise additional panels.

The support formation 360 can comprise a first support panel 361, a second support panel 362, and a third support panel 363. The first support panel 361 can be connected to the first main panel 310 by a line 371. The first support panel 361 can be connected to the second support panel 362 by a line 372. The second support panel 362 can be connected to the third support panel 363 by a line 373. The third support panel 363 can be connected to the second main panel 320 by a line 374. A glue pad 376 can be arranged on the first main panel 310 proximate the support formation 360. A glue pad 378 can be arranged on the third support panel 363.

The support formation 380 can comprise a first support panel 381, a second support panel 382, and a third support panel 383. The first support panel 381 can be connected to the third main panel 330 by a line 391. The first support panel 381 can be connected to the second support panel 382 by a line 392. The second support panel 382 can be connected to the third support panel 383 by a line 393. The third support panel 383 can be connected to the fourth main panel 340 by a line 394. A glue pad 396 can be arranged on the fourth main panel 340 proximate the support formation 380. A glue pad 398 can be arranged on the first support panel 381.

An inner surface 319 of the first main panel 310 can be seen. An inner surface 329 of the second main panel 320 can be seen. An inner surface 339 of the third main panel 330 can be seen. An inner surface 349 of the fourth main panel 340 can be seen.

An isolated view of the insert 3000 formed from the blank 300 can be seen with reference to FIG. 4. As can be seen, the connection panel 350 can be joined to the first main panel 310 by gluing, adhering, mechanically joining, or otherwise affixing the connection panel 350 to the first main panel 310.

In the current aspect, the connection panel 350 can be seen connected to an outer side of the first main panel 310. In various aspects, the connection panel 350 can be connected to various portions or surfaces of the first main panel 310.

The support formation 360 can be seen with the various elements in facing arranging. The first support panel 361 can be seen in facing contact with the second support panel 362. The third support panel 363 can be seen in facing contact

with the first main panel **310**. In the current aspect, the glue pad **376** can be arranged in contact with the glue pad **378** and can allow the support formation **360** to maintain its shape. The support formation **380** can be seen with the various elements in facing arranging. The second support panel **382** can be seen in facing contact with the third support panel **383**. The first support panel **381** can be seen in facing contact with the fourth main panel **340**. In the current aspect, the glue pad **396** can be arranged in contact with the glue pad **398** and can allow the support formation **380** to maintain its shape.

A packaging subassembly **1500** can be seen with reference to FIGS. **5A-5B**. With specific reference to FIG. **5A**, a collapsed insert **3000'** can be a collapsed version of the insert **3000** and can be arranged on the blank **200** formable into the box **2000**. The collapsed insert **3000'** can be assembled from the blank **300** and can be arranged with the first main panel **310**, second main panel **340**, first support panel **361**, and third support panel **383** in co-planar arrangement. In the current aspect, the first main panel **310** can be in contact with and mainly facing the second main panel **320** (not visible in the view of FIG. **5A**) and the fourth main panel **340** can be in contact with and mainly facing the third main panel **330** (not visible in the view of FIG. **5A**). Similarly, the collapsed insert **3000'** can be arranged with the second main panel **320**, the third main panel **330**, the second support panel **362**, the third support panel **363**, the first support panel **381**, and the second support panel **382** in co-planar arrangement (all features not visible in the view of FIG. **5A**). The blank **300** can be sized such that the collapsed insert **3000'** can fit within the space that would be occupied by the second main panel **220** and the third main panel **230**. The second support panel **362** can be arranged to be in contact with the glue pad **255**. The second support panel **382** can be arranged to be in contact with the glue pad **265**. As such, the collapsed insert **3000'** can be affixed to the blank **200** as part of the packaging subassembly **1500**.

Motion **299,399** can be shown as the folding of the blank **200** to form the outer box **2000** by securing the connection panel **250** to the first main panel **210**. Upon folding and adhering the connection panel **250** to the first main panel **210**, the insert **3000** can be formed from the collapsed insert **3000'** and the outer box **2000** can be formed from the blank **200**. As such, one manufacturing action can modify the packaging subassembly **1500** from a flattened state or collapsed state shown with reference to FIG. **5A** to an expanded state or assembled state shown with reference to FIG. **5B**. Additionally, the insert **3000** and blank **200** forming the packaging subassembly **1500** can be shipped in the flattened state of FIG. **5A** and can be stacked with additional packaging subassemblies **1500** to allow efficient delivery of the packaging subassemblies **1500** and efficient assembly of each packaging subassembly **1500** from the collapsed state to the expanded state.

In the current aspect, various features and parts of the packaging assembly **1000** can be formed of various paper products, including paperboard, corrugated cardboard, kraft paper, and various other materials. In various aspects, the blanks **200,300** can be formed of varying materials including various plastics, metals, wood, or various other elements. In various aspects, the blanks **200,300** can be a combination of materials described herein or known within the relevant art. In various aspects, the packaging of the current disclosure can be formed without the use of a blank such as the blanks **200,300**. One of skill in the art would understand that use of the blanks **200,300** is but one method of assembling the packaging of the current disclosure.

In the current aspect, various surfaces can be covered by a temperature-preserving lining. In various aspects, the temperature-preserving lining can be a product adhered to a surface of the blanks **200,300**. In various aspects, the temperature-preserving lining can be a film adhered to the surface of one of the blanks **200,300**. Films can be adhered to surfaces through various methods, including adhesion (such as with glues or chemical adhesives) or by deposition (such as by vapor deposition) among other methods. In various aspects, the film temperature-preserving lining can be a highly reflective coating. Such a highly reflective surface can be of low emissivity, thereby serving as an effective insulating material. Examples of coatings or films that can be used for temperature-preserving linings can be found with reference to United States Patent Application of Sollie, filed Jul. 14, 2023, bearing application Ser. No. 18/222,272, which is incorporated by reference herein in its entirety. In various aspects, the blanks **200,300** can include the temperature-preserving lining on all sides. In various aspects, the blanks **200,300** can include the temperature-preserving lining on only one side to reduce costs. In various aspects, temperature-preserving lining can be omitted.

The inner surfaces **319,329,339,349** can together form an inner surface of the insert **3000**. In particular, temperature-preserving lining can be adhered to the inner surface of the insert **3000**. With reference to FIG. **5B**, inner surfaces **329,339,349** of the main panels **320,330,340**, respectively, can be seen.

A bottom insulation pad **6000** can be seen with reference to FIG. **6**. The bottom insulation pad **6000** can be sized to fit within the insert **3000** along a bottom of the outer box **2000**. The bottom insulation pad **6000** can be an insulating pad, batt, or otherwise insulating material. In the current aspect, each insulator can be a physical object of insulating capacity such as an insulating pad, an air-filled bag, added cardboard, added paper product, paper fill, or various other insulation. In the current aspect, the bottom insulation pad **6000** can be representative of all different forms of insulation utilized with the packaging assembly **1000**. The bottom insulation pad **6000** can be an insulation batt on its own. The bottom insulation pad **6000** can be an insulation batt encapsulated within a paper capsule. The paper capsule can be a first paper layer secured to a second paper layer and sealed around a perimeter of the insulation batt to encapsulate the insulation batt. In various aspects, the insulation batt can be repulpable. Further description of aspects of some insulators that can be used in the packaging assembly **1000** can be found with reference to the following United States Patents and Applications for United States Patent, which are incorporated by reference herein in their entirety: U.S. patent application Ser. No. 17/834,999, filed Jun. 8, 2022, (issued as U.S. Pat. No. 11,780,666 on Oct. 10, 2023); U.S. patent application Ser. No. 17/502,599, filed Oct. 15, 2021 (issued as U.S. Pat. No. 11,634,265 on Apr. 25, 2023); U.S. patent application Ser. No. 17/123,673, filed Dec. 16, 2020 (issued as U.S. Pat. No. 11,214,427 on Jan. 4, 2022); U.S. patent application Ser. No. 16/414,309, filed May 16, 2019 (issued as U.S. Pat. No. 10,882,682 on Jan. 5, 2021); U.S. patent application Ser. No. 15/677,738, filed Aug. 15, 2017 (issued as U.S. Pat. No. 10,583,977 on Mar. 10, 2020); U.S. Provisional Application Nos. 62/375,555, filed on Aug. 16, 2016; 62/419,894, filed on Nov. 9, 2016; and, 62/437,365, filed on Dec. 21, 2016.

A bottom insulation cover **7000** as can be utilized in various aspects of the current disclosure can be seen with reference to FIG. **7**. The bottom insulation cover **7000** can comprise a main panel **7001**; a first side panel **7010** connected to the main panel **7001** by a line **7015**; a second side

panel **7020** connected to the main panel **7001** by a line **7025**; a third side panel **7030** connected to the main panel **7001** by a line **7035**; and, a fourth side panel **7040** connected to the main panel **7001** by a line **7045**. The side panels **7010,7020, 7030,7040** can be arranged to surround the bottom insulation pad **6000** and the main panel **7001** can be arranged to provide a barrier between the bottom insulation pad **6000** and any contents to be placed within the packaging assembly **1000**.

A blank **800** for forming a vented cover (not seen in the current view) can be seen with reference to FIG. 8. The blank **800** can comprise a main panel **801**; a first end panel **810** connected to the main panel **801** by a line **815**; a second end panel **820** connected to the main panel **801** by a line **825**; a third end panel **830** connected to the main panel **801** by a line **835**; and, a fourth end panel **840** connected to the main panel **801** by a line **845**. The main panel **801** can define a plurality of vents **850**. In the current aspect, eighteen vents **850** of circular cross-section can be defined in the main panel **801**. In the current aspect, each vent **850** is of about circular cross-section. In various aspects, vents **850** can be of different shapes and sizes. In various aspects, vents **850** can be omitted from the design of the current disclosure. In assembly, the blank **800** can be formed to fit within the insert **3000** and provide a physical barrier between the contents of the packaging assembly **1000** and any environment outside of the packaging assembly **1000**.

Another aspect of a vented cover **8000'** can be seen with reference to FIGS. 9A-9B. The vented cover **8000'** can comprise a top **8001**, a first side **8010**, a second side **8020**, a third side **8030**, and a bottom **8002**. In various aspects, a fourth side can be included. In the current aspect, a fourth side can be omitted. Similarly to the blank **800**, the top **8001** can define a plurality of vents **8850**. In the current aspects, each vent **8850** can be an oblong shape and defined in the top **8001**. In the current aspect, twenty-two vents **8850** can be defined in the top **8001**. The various features of the vented cover **8000'** can be arranged to define a gap **8852** between the top **8001**, the first side **8010**, the second side **8020**, the third side **8030**, and the bottom **8002**. Top vented cover **8000'** can be inserted in the packaging assembly **1000** within the insert **3000** to provide an insulated top end to the packaging assembly **1000**. In various aspects, the vented cover **8000'** can contain an insulation material or insulated pad similar to the bottom insulation pad **6000** within the gap **8852**.

An insulation element **4000** or insulation pad can be seen with reference to FIGS. 10A-10B. Each insulation element **4000** can be an insulating material similar to bottom insulation pad **6000**, described above. In various aspects, the insulation element **4000** can be various materials similar to bottom insulation pad **6000**. In various aspects, each insulation element **4000** can be an insulation batt surrounded by kraft paper as previously described. Each insulation element **4000a,4000b** described with brief reference to FIG. 1 can be an insulation element **4000**. Each insulation element **4000** can be sized to fit within a space defined between the outer box **2000** and the insert **3000**. In various aspects, each insulation element **4000** can be rectangular with a bend located at a point somewhere within the insulation element **4000** allowing each insulation element **4000** to accommodate the shape of the box **2000** and the insert **3000**.

Various aspects of the packaging assembly **1000** can be seen with reference to FIGS. 11A-11C. With specific reference to FIG. 11A, the bottom insulation pad **6000** can be seen inserted within and arranged inside the insert **3000** within the outer box **2000**. With reference to FIG. 11B, the

bottom insulation cover **7000** can be seen arranged over the bottom insulation pad **6000** inside the insert **3000** within the outer box **2000**. With specific reference to FIG. 11C, the vented cover **8000'** can be seen arranged within the insert **3000** within the outer box **2000**. Gaps **9010a, 9010b** can be defined between the insert **3000** and the outer box **2000**. In various aspects, the gaps **9010a,9010b** can be left empty. As seen with reference to FIG. 1, the caps **9010a,9010b** can be filled with insulation pads **4000a,4000b**. in various aspects, 10 various features can be utilized with gaps **9010a,9010b**.

In various aspects, various features can be included and omitted as would be understood to one of skill in the art. One of skill in the art would understand the various features and elements described here can be interchangeably moved between various aspects without departing from the scope of the current disclosure. No single aspect should be considered limiting on the scope of this disclosure.

One should note that conditional language, such as, among others, "can," "could," "might," or "may," unless 20 specifically stated otherwise, or otherwise understood within the context as used, is generally intended to convey that certain embodiments include, while other embodiments do not include, certain features, elements and/or steps. Thus, such conditional language is not generally intended to imply that features, elements and/or steps are in any way required for one or more particular embodiments or that one or more particular embodiments necessarily include logic for deciding, with or without user input or prompting, whether these features, elements and/or steps are included or are to be 25 performed in any particular embodiment.

It should be emphasized that the above-described embodiments are merely possible examples of implementations, merely set forth for a clear understanding of the principles of the present disclosure. Any process descriptions or blocks 30 in flow diagrams should be understood as representing modules, segments, or portions of code which include one or more executable instructions for implementing specific logical functions or steps in the process, and alternate implementations are included in which functions may not be included or executed at all, may be executed out of order from that shown or discussed, including substantially concurrently or in reverse order, depending on the functionality involved, as would be understood by those reasonably skilled in the art of the present disclosure. Many variations 35 and modifications may be made to the above-described embodiment(s) without departing substantially from the spirit and principles of the present disclosure. Further, the scope of the present disclosure is intended to cover any and all combinations and sub-combinations of all elements, features, and aspects discussed above. All such modifications and variations are intended to be included herein within the scope of the present disclosure, and all possible 40 claims to individual aspects or combinations of elements or steps are intended to be supported by the present disclosure.

That which is claimed is:

1. A packaging assembly comprising:
an outer box, the outer box comprising a first main panel connected to a second main panel, a third main panel connected to the second main panel, and a fourth main panel connected to the third main panel, the fourth main panel connected to the first main panel;
an insert connected to at least two of the main panels of the outer box, the insert comprising:
a first main panel connected to a second main panel;
a third main panel connected to the second main panel;
and

a fourth main panel connected to the first main panel and the third main panel, wherein at least one support formation folds from at least two of the four main panels of the insert,
wherein

each support formation comprises a first support panel, a second support panel connected to the first support panel at a first bend line, and a third support panel connected to the second support panel at a second bend line;

the first support panel is in facing contact with the second support panel;

each support formation connects the insert to the outer box; and

the insert is folded from a blank;

wherein a continuous gap is defined between two adjacent main panels of the insert and two corresponding adjacent main panels of the outer box.

2. The packaging assembly of claim 1, wherein the insert is arranged within the outer box.

3. The packaging assembly of claim 2, wherein at least one gap is defined between the insert and the outer box.

4. The packaging assembly of claim 3, wherein an insulation pad is arranged within each gap.

5. The packaging assembly of claim 4, wherein two gaps are defined between the insert and the outer box.

6. The packaging assembly of claim 2, further comprising a bottom insulation pad arranged within the insert.

7. The packaging assembly of claim 6, further comprising a bottom insulation cover in contact with the bottom insulation pad.

8. The packaging assembly of claim 2, further comprising a vented cover arranged within the insert.

9. The packaging assembly of claim 1, wherein the insert is connected to the second main panel and the third main panel of the outer box.

10. The packaging assembly of claim 9, wherein each connection of the insert to the outer box is by a glue pad.

11. The packaging assembly of claim 1, wherein an inner surface of the insert is coated with a temperature-preserving lining.

12. The packaging assembly of claim 1, wherein the first main panel of the insert, the second main panel of the insert, the third main panel of the insert, and the fourth main panel of the insert define a cavity.

13. The packaging assembly of claim 1, wherein each support formation is connected to two of the four main panels of the outer box at the first bend line of the support formation and the second bend line of the support formation.

14. The packaging assembly of claim 13, wherein the first bend line of the support formation and the second bend line of the support formation are scored on the blank.

15. A packaging assembly comprising:
an outer box, the outer box comprising a first main panel connected to a second main panel, a third main panel connected to the second main panel, and a fourth main panel connected to the third main panel, the fourth main panel connected to the first main panel;

an insert arranged within the outer box and defining at least one gap between the insert and the outer box, the insert comprising

a first main panel connected to a second main panel; a third main panel connected to the second main panel; and

a fourth main panel connected to the first main panel and the third main panel, wherein at least one support formation folds from at least two of the four main panels of the insert;

wherein

each support formation comprises a first support panel, a second support panel connected to the first support panel at a first bend line, and a third support panel connected to the second support panel at a second bend line;

each support formation connects the insert to the outer box; and

the insert is folded from a blank;

wherein a continuous gap is defined between two adjacent main panels of the insert and two corresponding adjacent main panels of the outer box.

16. The packaging assembly of claim 15, wherein each gap is filled with an insulation element.

17. The packaging assembly of claim 15, wherein at least one first support panel is in facing contact with one second support panel.

18. The packaging assembly of claim 15, wherein at least one support formation comprises a glue pad connecting at least one support panel to at least one other support panel.

19. The packaging assembly of claim 15, wherein the insert is connected to the second main panel and the third main panel of the outer box.

20. The packaging assembly of claim 19, wherein each connection of the insert to the outer box is by a glue pad.

21. The packaging assembly of claim 15, wherein each support formation is connected to two of the four main panels of the outer box at the first bend line of the support formation and the second bend line of the support formation.

22. The packaging assembly of claim 21, wherein the first bend line of the support formation and the second bend line of the support formation are scored on the blank.

23. The packaging assembly of claim 15, wherein the first main panel of the insert, the second main panel of the insert, the third main panel of the insert, and the fourth main panel of the insert define a cavity.
